M. E. CHAMBERLAIN.
TIE.
APPLICATION FILED APR. 10, 1915.

1,149,632.

Patented Aug. 10, 1915.

UNITED STATES PATENT OFFICE.

MINOR E. CHAMBERLAIN, OF LEBANON, MISSOURI.

TIE.

1,149,632.

Specification of Letters Patent.

Patented Aug. 10, 1915.

Application filed April 10, 1915. Serial No. 20,435.

To all whom it may concern:

Be it known that I, MINOR E. CHAMBERLAIN, a citizen of the United States, residing at the city of Lebanon, county of Laclede, and State of Missouri, have invented a new and useful Tie, of which the following is a specification.

This invention relates to rail ties, and it has particular reference to ties composed of concrete and provided with metallic reinforcements.

An object of the invention is to provide a monolithic concrete tie having a number of reinforcements embedded therein, each of said reinforcements comprising a metallic sheet folded to provide a number of horizontally disposed wings, two of which are of double thickness and the remaining two of single thickness of the sheet, connections uniting one of the wings of single thickness on one of said reinforcements with one of the wings of single thickness on the other reinforcement, and means for securing the rails to the ties.

Another object is to provide an improved concrete rail tie comprising a concrete body, a number of parallel reinforcements embedded in said concrete body and each comprising a metallic sheet folded to provide a number of wings, at least one of said wings in each reinforcement being of a double thickness of the sheet and another of said wings of a single thickness of the sheet, and metallic connections uniting the wings of single thickness, in combination with rail supports, means for securing said rail supports to the tie, and means for securing the rails upon said supports.

Additional objects of my invention will appear from the following description, reference being made to the accompanying drawing in which I have illustrated a suitable embodiment of the invention and in which—

Figure 1 is a plan view of two ties having the rails secured thereto. Fig. 2 is a side elevation of the tie. Fig. 3 is a longitudinal vertical sectional view approximately on the line 3—3 of Fig. 1. Fig. 4 is a longitudinal horizontal sectional view approximately on the line 4—4 of Fig. 2. Fig. 5 is a perspective view of the tie before the rail supports are placed in position in connection with the tie. Fig. 6 is an end elevation of a tie. Fig. 7 is a view which is enlarged with respect to the preceding

views, and being a sectional view on the line 7—7 of Fig. 2. Fig. 8 is a perspective view of the rail base plate. Fig. 9 is a perspective view of one of the devices by which the rails are held in position.

The tie consists of a monolithic concrete body 1 of suitable dimensions and shape. Within the concrete body 1 are embedded two parallel metallic reinforcements 2, each of which is composed of sheet metal folded to provide four horizontally disposed wings, two of which are of a double thickness and the remaining two of which are of a single thickness of the sheet. The wings of double thickness extend in vertical planes within the concrete body, and the wings which are of single thickness extend in horizontal planes, so that one of the wings of single thickness on one of said reinforcements extends toward one of the wings of single thickness on the other reinforcements. By arranging the reinforcements so that the wings of double thickness are in vertical planes within the concrete body it is obvious that said reinforcements will be better enabled to resist the stresses and strains to which the tie is subjected, since most of the stresses and strains come from above the tie. Each outwardly extending wing of single thickness is equipped with an auxiliary reinforcement 3 which is formed of sheet metal folded to provide a double portion between which the wing of single thickness of the reinforcement 2 is received, and also to provide two vertically extending portions of single thickness which abut against the vertically disposed wings of double thickness of the main reinforcements 2. The reinforcements 3 are preferably secured in connection with the reinforcements 2 by stamping lateral extending tongues 4 from the overlapping portions of said reinforcements.

The reinforcements 2 are parallel, and are arranged in substantially the same horizontal plane. The inwardly extending wing of single thickness on one of said reinforcements is connected with the adjacent wing of single thickness on the other reinforcement by metallic connections 5, each connection comprising two sheet metal plates whose intermediate portions are connected by rivets 6 or other suitable fastening devices, and whose ends extend above and below the wings of single thickness on said reinforcements 2. Thus, the two longitudinal reinforcements 2 are united by auxiliary

reinforcements, so that each reinforcement affords additional strength to the other. The ends of the connections 5 are secured to the lateral wings of the reinforcements 2 5 by suitable fastening devices 7.

In the upper side of the tie near each end thereof, a recess 8 is formed of suitable size to receive a rail support 9, preferably of wood or other suitable material and of a 10 size sufficient to support the rails and afford the necessary or desired resiliency. The supports 9 are seated within the recess 8, and are above the metallic reinforcements, as will be understood by reference to Figs. 3 15 and 7. The concrete is provided with two holes 10 below each of the recesses 8, and fastening bolts 11 extend through said holes 10 and through holes in the rail supports 9. A metallic rail seat is supported upon each 20 of the rail supports 9, and includes a plate portion 12 seated upon the support 9 and provided with holes 13 through which the bolts 11 extend. The plate 12 is provided with two depending flanges 14 which engage 25 opposite sides of the rail support 9 and thereby coöperate with the bolts 11 to retain the rail seat in position on the support. The rail 16 is seated between two vertical flanges 15 on the rail seat 12, said flanges engaging 30 the opposite edges of the base of the rail and thereby preventing lateral movement of the rail upon the seat. The rail is further retained in position by metallic arms 17 which have holes through which the bolts 11 35 extend, and which are prevented from displacement from the bolts by the clamping nuts 18 upon the upper ends of said bolts. Each of the arms 17 is provided with a shoulder 19 bearing against the adjacent 40 flange 15 and thus preventing the clamping arm 17 from being turned from its position. The end of each of the arms 17 extends over and bears against the upper surface of the 45 base of the rail, while the inner ends of said clamping arms bear against the vertical sides of the web of the rail, thus coöoperating with the shoulder 19 and the flanges 15 to prevent the clamping arms from being dislocated.

A tie constructed in accordance with the 50 foregoing description and illustration is very simple and durable. The reinforcements are wholly embedded within the concrete so that they are not subject to corrosion. The provision of the reinforcements 55 with the vertically disposed wings of double thickness, the efficiency of which is increased by the auxiliary reinforcements, provides a tie which will resist all of the ordinary stresses and forces to which the tie will be 60 subjected.

It will be obvious that there may be various alterations and modifications in the construction of the tie and the various parts and elements thereof without departing 65 from the principles and scope of the inven-

tion. Therefore, I do not restrict myself to precise features of construction or arrangement, but

What I claim and desire to secure by Letters Patent is:

1. A tie, comprising a concrete body, a number of parallel reinforcements embedded in said body and each comprising a single sheet folded to provide four wings two of which are of double thickness and two of which are of a single thickness of the sheet, the wings of double thickness being in vertical planes and the wings of single thickness being in horizontal planes, a number of metallic elements connecting one of the wings 75 of single thickness on one of said reinforcements with one of the wings of single thickness on the other reinforcement, and means for securing rail supports to said concrete body. 80

2. A reinforced concrete tie, comprising a concrete body having recesses in its upper side for receiving rail supports, a number of parallel reinforcements embedded in said body below said recesses, and each comprising a single sheet of metal folded to provide two wings of double thickness in a vertical plane, and a wing of single thickness arranged in a horizontal plane, said wings of single thickness extending toward each 90 other, and metallic plates connecting said wings of single thickness, a number of said plates being below said recesses. 95

3. A concrete tie, comprising a concrete body having recesses in its upper side, a number of parallel reinforcements embedded in said body and each comprising a metallic sheet folded to provide two wings of double thickness in a vertical plane and one wing of single thickness in a horizontal plane, an auxiliary reinforcement comprising a metallic sheet folded to provide a double portion clamped upon said wing of single thickness, vertically disposed wings of single thickness on said auxiliary reinforcement bearing against the wings of double thickness on said first-named reinforcements, and means securing said auxiliary reinforcement in engagement with said wings of single thickness. 100

4. A concrete tie, comprising a concrete body, metallic reinforcements embedded in said concrete body and each comprising a metallic sheet folded to provide two vertical wings of double thickness of the sheet and two horizontal wings of single thickness of the sheet, metallic plates connecting one of the wings of single thickness on one of said reinforcements with one of the wings of single thickness on the other reinforcement, 105 an auxiliary reinforcement connected to the other wing of single thickness on each of said reinforcements, said auxiliary reinforcement comprising a metallic plate folded to provide a double portion clamped 110 115 120 125 130

upon the wing of single thickness and two vertically disposed wings of single thickness bearing against the wings of double thickness of said first-named reinforcements, 5 and means for holding the rails in connection with said tie.

5. A concrete tie, comprising a concrete body, a number of parallel reinforcements embedded in said body and each comprising 10 a single sheet folded to provide four wings two of which are of double thickness and two of which are of a single thickness of the sheet, the wings of double thickness being in vertical planes and the wings of single 15 thickness being in horizontal planes, an auxiliary reinforcement comprising a metallic sheet folded to provide a double portion clamped upon one of said wings of single thickness of each reinforcement, a number 20 of metallic elements connecting said parallel reinforcements, and means for securing rail supports to said concrete body.

6. A reinforced concrete tie, comprising a concrete body having recesses in its upper 25 side, a number of parallel reinforcements

embedded in said concrete body and each comprising a metallic sheet folded to provide two vertical wings of double thickness and two horizontal wings of single thickness of the sheet, in combination with an auxiliary reinforcement for each of said 30 first-named reinforcements, each of said auxiliary reinforcements comprising a metallic plate folded to provide a double portion clamped upon one of said wings of single thickness, and to provide two vertical wings of single thickness bearing against said vertical wings of double thickness of said first-named reinforcements, metallic 35 connections between said reinforcements, and 40 passages through said concrete body between said reinforcements and said connections for rail securing elements.

In witness whereof, I have signed this specification in the presence of two subscribing witnesses.

MINOR E. CHAMBERLAIN.
